ANTENNA COUPLING AND TUNING SYSTEM
FOR COMMUNICATION OR BROADCAST
RECEIVERSClarence W. Wandrey, Chicago, Ill., assignor to
Zenith Radio Corporation, a corporation of Illinois

Application April 21, 1941, Serial No. 389,650

48 Claims. (Cl. 192—142)

The present invention relates to control systems and apparatus and more especially to improvements in circuit adjusting apparatus for radio receivers. This application is a continuation in part of the application of Clarence W. Wandrey and James W. Sharp, Serial No. 359,124 filed September 30, 1940, for Antenna coupling and tuning system for communication or broadcast receivers.

It is a general object of the present invention to provide novel control apparatus of general use in a wide variety of electrical equipment, including laboratory apparatus, power generation apparatus and motive power equipment, and also tunable apparatus such as radio transmitters and receivers.

Another object of the present invention is to provide novel control systems for adjustable circuits.

Another object of the present invention is to provide novel control means for the circuit changing elements of adjustable electrical circuits.

Another object of the present invention is to provide tuning apparatus especially adapted for use in compact radio equipment such as marine, aircraft and automobile radio equipment.

A further object of the present invention is to provide for operation, in a novel manner, of the tunable elements of a radio receiver.

A still further object of the present invention is to provide novel means for tuning a radio receiver to any one of a plurality of predetermined signal sources.

A still further object of the present invention is to enable ready and convenient adjustment of any one of a plurality of selectable tuning positions at will.

A still further object of the present invention is to provide novel tuning apparatus in the manufacture of which accurate machine work to close tolerance is not required, and wherein loose fitting parts and play between the parts or either will not affect accuracy of tuning.

It is a further general object of the present invention, in one aspect thereof, to provide novel antenna tuning and high frequency energy transfer circuits, and in another aspect, to provide novel control systems for tunable circuits.

In coupling a radio receiver to an antenna circuit having very low capacity, it is difficult to obtain maximum transfer of signal energy. Also, it is difficult with an antenna of this type to obtain a signal for use in the receiver which is free from interference and locally produced noise.

In dealing with a small low capacity antenna of very high impedance, such as a simple insulated short rod, difficulties are encountered in obtaining efficient transfer of energy. Antenna coupling circuits of the prior art are only imperfectly adapted to couple antennae of the type just mentioned to the input circuits of a radio receiver and these known coupling circuits have inherent defects which cannot be avoided in practice. They have limited range or frequency spectrum coverage in use, and can transfer only a small portion of a desired frequency or wave length band. Wide variations in coupling are experienced as the adjustable circuits which they employ are adjusted or tuned to select a desired signal source. From a practical standpoint, these previously known antenna coupling arrangements cannot be effectively used especially where space is a factor as in a broadcast receiver for installation in aircraft, or a vehicle such as an automobile, since these known tuners do not lend themselves to compactness of design, flexibility or ease of control. Apparatus embodying circuits available prior to this invention could not be designed for ease and cheapness of manufacture, thereby to conserve materials, reduce the cost of material and eliminate unnecessary and costly manufacturing operations. Practical control equipment of suitable design for ordinary or special purposes could not be used effectively with these prior art coupling circuits. In this connection, as stated above, the present invention aims to provide novel tuning apparatus of general use in a wide variety of tunable equipment, and this novel apparatus is especially suited for use in the field of compact radio apparatus such as aircraft and automobile radio receivers employing high impedance low capacity antennae.

Accordingly, one of the major objects of the present invention is to provide improved signal energy transfer from an antenna to the input circuit of a radio or broadcast receiver.

Another important object of the present invention is to overcome the difficulties mentioned above, and other difficulties which are inherently present in prior art adjustable circuits and controls for the adjustable elements of these circuits.

Still another object of the invention is to provide novel circuits, adjustable for tuning, which will permit the maximum transfer of signalling energy from a carrier receiving device, such as an antenna, to a translating device such as, for

example, an amplifier in a radio receiver or other repeating device.

A still further object of the invention is to provide novel tunable circuits which will reduce interference caused by undesired oscillations from sources external to the receiver. 5

A still further object of the invention is to provide a novel antenna coupling circuit in a superheterodyne radio receiver, permitting use of a lower intermediate frequency while at the same time providing separation between the desired frequency and any interfering frequency. 10

A still further object of this invention is to provide a novel form of coupling between the amplifying portions of a radio receiver and an antenna of high impedance, which coupling will provide uniform sensitivity throughout a desired tuning range. 15

The manner of realizing the foregoing objects and obtaining the general and special advantages discussed above and, also, other and more specific objects of the invention will become apparent as the following detailed description proceeds with reference to the accompanying drawings of which:

Figure 1 is a diagrammatic showing of electrical and mechanical features of the present invention embodied in a radio receiver, certain parts of which are shown in a conventional manner.

Figure 2 is a fragmentary detail of the apparatus of Figure 1 drawn to an enlarged scale and illustrating another position of the parts.

Figures 3 and 4 are additional fragmentary details drawn to an enlarged scale.

Figure 5 is a diagrammatic representation of the antenna tuning and coupling circuit of this invention in one form.

Figure 6 is a plan view, partially in section on line 6—6 of Figure 7, of a radio receiver showing the invention in a modified form, certain parts of the receiver being omitted for the sake of clearness of illustration.

Figure 7 is a vertical section taken on line 7—7 of Figure 6 as viewed in the direction of the arrows.

Figures 8 and 9 are fragmentary detail views of the modification of Figure 6.

Figure 10 is a view in front elevation of the receiver of Figure 6.

Figure 11 is a diagrammatic showing of the electrical connections of the tuning device of Figures 6 to 10.

Figure 12 is a diagrammatic showing of electrical and mechanical features of another modification of the tuner control of this invention. 55

Figure 13 illustrates a detail of the modification of Figure 12.

Figure 14 is a view similar to Figure 6 illustrating a further modification of the invention taken on line 14—14 of Figure 15.

Figure 15 is a vertical section taken on line 15—15 of Figure 14.

Figures 16 and 17 are fragmentary detail views of the receiver of Figure 14.

Figure 18 is a view of the front elevation of the receiver in Figure 14.

Figure 19 is a diagrammatic showing of the electrical connections of the tuning device of Figure 14. 70

Figures 20 and 21 are fragmentary detail views of certain connections illustrated diagrammatically in Figure 19.

Certain of the figures of the drawings disclose the invention as being embodied in a radio re-

ceiver designed more especially for use in a vehicle. It is to be understood, however, that the invention is not so limited. Referring to Figure 1, reference character 5 indicates the various sections of the receiver which are more or less conventional. All of the circuits of the receiver are not shown but the circuits necessary for an understanding of this invention are shown externally of the diagrammatic representation 5. One of these externally shown circuits is the antenna 6 together with the associated antenna coupling and radio frequency tuning circuit indicated generally by the reference character 7, which includes tunable inductances 8 and 9 and a trimmer condenser 10. The portion 7 of the receiver, which cooperates in a novel manner with radio frequency amplifier 14 is an important feature of the present invention and will be explained more in detail hereinafter in connection with the description of Figure 5 illustrating an equivalent circuit for the antenna 6. 15

Reference character 16 indicates the oscillator frequency control circuit which is shown connected to the oscillator and mixer section of the set. This oscillator control circuit, which in actual practice forms an internal part of the oscillator and functions in the usual manner, comprises a tunable inductance 17 effectively connected in parallel with an inductance 18 which is inductively coupled to a "tickler" coil 19. 20

The combined station selecting device and station pre-setting device, indicated generally by reference character 21, is an important feature of the invention and is illustrated in modified form in Figures 6 to 9. The fundamental features and principles of operation of the device 21 will now be explained with reference to the diagrammatic showing on Figures 1 to 4 of the drawings. 25

Tuning is accomplished by a plurality of longitudinally movable cores 23, preferably manufactured from ferrous materials. In the embodiment shown in Figure 1, which illustrates the fundamental features of this aspect of the invention, three cores 23 are required, which cooperate with inductively tuned antenna tuning circuit inductances 8 and 9 and the inductance 17 for the oscillator circuit 16. It will be understood that when the device 21 is adapted for use with other types of receivers the cores 23 will vary in number and location. The cores 23 are adjustably secured as at 26 to a yoke member 27 which forms a part of a movable carriage 28 comprising the above mentioned yoke member, a solenoid core 29 and a suitable connecting link such as the member 31 which joins the solenoid core to the yoke 27. Means, illustrated as the guide member 32 which is rigidly secured to a stationary portion of the receiver, serves to support and guide the carriage 28 for longitudinal movement. Means, such as the compression spring 33, surrounding the member 31 and reacting between one arm 34 of the guide 33 and a disc or other member 36 suitably secured to the connecting member 31, tends to move the carriage 28 to the left as viewed in Figure 1 and serves to maintain the yoke member 27 in a position determined by one of a plurality of stops or abutments 37 or 37A, which contacts the member 38 (Figure 3) pivoted at 39 to the yoke 27. The member 38 is maintained in position to contact a stop 37 in selected position by spring 40. These springs permit the stops 37 to revolve about the axis of the shaft 44 without interference from

the member 38 permitting any position of the stops to be selected at will.

From the parts thus far described, it will be seen that as the carriage 28 is moved to the left, cores 23 will enter the inductances 8, 9 and 17 and thereby progressively increase their inductance to effect tuning of the circuits with which these inductances are associated. When this progressive movement is arrested at any given point, the tunable circuits including these inductances will be tuned to a given frequency. The stops 37 serve to arrest movement of the carriage 28, there being as many positions of rest for the carriage as there are stops 37, and hence the tuned circuits will be in resonance for one frequency for each stop thereby providing ready means for selecting, one at a time, a predetermined number of different frequencies. These frequencies may be those assigned to a plurality of broadcast stations thus affording convenient means for selecting a desired broadcast station.

The carriage 28 is moved longitudinally in a continuous manner to effect manual tuning, a desired stop 37 being positioned to arrest movement of the carriage; the several stops being arranged so that they may be individually adjusted or pre-set by mechanism operated from a handle or knob 41 and now to be described.

To the end that any desired stop 37 may be positioned to arrest movement of the carriage 28, these stops are carried by discs 42 and 43 which are secured upon and rotate with the shaft 44. In the embodiment shown, each stop 37 is provided with a threaded stem 47, which receives and supports an internally threaded pinion 48. The stop 37A carries a pinion 49 which cooperates with a gear 51, and which is preferably internally threaded with a higher pitch thread so that the stop 37A may be moved longitudinally at a higher speed by which manual tuning is effected in a manner later to be described. As a given pinion 48 or the pinion 49 is brought into the position occupied by the pinion 49 in Figure 1 of the drawings, the stop associated with the pinion will be moved longitudinally in a direction which depends upon the direction of rotation of the pinion.

The shaft 44 is mounted for rotation in suitable bearings which may be integral with or secured upon a mounting plate (not shown) and this plate may also carry the guide 32. A bevel gear 53 on the shaft 44 meshes with a similar gear 54 which is journaled in a stationary bearing member 56. A shaft 57, which has secured at its end the handle or knob 41 previously described, is slidably and rotatably journaled in suitable bearings (not shown) and is keyed or splined in the bevel gear 54.

A third shaft 61 extends at right angles to the shaft 57 and lies in a plane at a different elevation from that of the knob shaft 57. This third shaft 61 is slidably and rotatably journaled in suitable bearings (not shown). The shaft 61 is biased toward the right in Fig. 1 by a compression spring 61' and carries the previously mentioned gear 51 which is secured thereto. The gear 51 is adapted to mesh with a gear 62 secured to a shaft 63 and carries a tuning knob or hand wheel 64 which may project through an aperture 66 in an escutcheon plate 67 or other casing member whereby it can be readily manipulated by hand.

From the description of the parts including the shafts 61 and 63, it will be observed that

as the shaft 61 is shifted to the left as viewed on Figure 1, the gear 51 will mesh with gears 48 or 49 and the gear 62 whereby upon turning the knob 64, the stops 37 or the stop 37A, respectively, will be moved longitudinally. When the stop 37A occupies the position shown so as to move the carriage 28 and the tuning cores 23, rapid manual tuning of the receiver is provided throughout its entire range. The assembly, including the discs 42 and 43 carrying the stops 37 and 37A, is rotated to place any of these stops in the position shown as occupied by stop 37A on Figure 1 of the drawings whereby to arrest movement of the yoke member 27 by engagement 15 with the member 38 projecting therefrom.

This rotation of the discs 42 and 43 is accomplished in the following manner: As the knob 41 is rotated, gears 53 and 54 turn the shaft 44. When the knob 41 is rotated to its extreme position in a counter-clockwise direction as viewed from the bottom of Figure 1, a radially projecting member 72 (Figs. 1 and 2) engages the projection 73 on the shaft 61 moving the latter towards the left to bring gear 51 into meshing 20 engagement with the gears 49 and 62 so that continuous and rapid manual tuning may be obtained as mentioned above. As hereafter explained, the carriage 28 is automatically withdrawn to the right in Fig. 1 by the solenoid 79 25 and returned to the left by the spring 33 each time the knob 41 is rotated.

Pre-setting of the stops 37 so that desired stations may be selected at will is provided for in the following manner: A member 76 having a conical shaped cam 77 is secured to the shaft 57 and may be of unitary construction with the stop 72 if desired. When the shaft 57 is drawn outwardly by means of the knob or handle 41 the conical cam 77 engages the previously described member 73 to effect movement of the shaft 61 toward the left thereby engaging the gears 49, 51 and 62.

With the parts in this position any one of the stops 37 which is in the position occupied by the stop 37A in Fig. 1 may be adjusted by rotating the knob 64 to move the carriage 28 to and fro to position the cores 23 relative to the inductances 8, 9 and 17 to tune in a desired station at that setting.

After a stop 37 has been adjusted to tune in a desired station the knob 41 may be pushed inwardly, rotated to any other desired position and pulled outwardly to effect adjustment for pre-selection of other stations. After the stops 37 have been set in this manner knob 41 may be pressed inwardly and as further described below the series of selected stations will be received as the knob is turned.

Energization of the solenoid 79 for the previously mentioned core 29 withdraws the carriage 28 toward the right as viewed in Figure 1 when the knob 41 is turned for any purpose such as to select a pre-set station, to select the manual tuning position for the stop 37A or to select any given stop 37 for adjustment to a new position.

To energize the solenoid 79 immediately upon turning the knob 41 a switch indicated diagrammatically at 81 and comprising a movable contact 82 is positioned so that the contact 82 is operated by a notched cam 83 rotatable with the shaft 57. A power source indicated at 84, which may if desired be the source supplying the several units of the radio receiver energizes the coil 79 immediately upon closure of the contacts of the switch 81 which causes the solenoid core 29

4

and carriage 28 to be withdrawn toward the right. Energization of the coil 79 is maintained by a locking circuit including the relay contacts 86 and 87, the latter contact being carried by an armature 88 which is attracted to circuit closing position by flux from the coil 79 when it is energized. When the core 29 is at or adjacent its full limit of travel to the right, member 89 projecting therefrom separates the contacts 86 and 87, thus permitting the core 29 and its associate carriage 28 to move to the left into engagement with the stop 37 or 37A just selected by rotation of the knob 41.

When desired, as pointed out above, the entire frequency range of the receiver may be covered rapidly by the tuning knob 64 which corresponds to the usual tuning knob in the ordinary radio receiver. With the parts in the position of Figure 1 of the drawings, the shaft 61 carrying the idler gear 51 will be in mesh with the tuning knob gear 62 and the pinion 49 on the stem of stop 31A. Turning of the tuning dial 64 will move the entire carriage 28, including the cores 23, from one extreme end of their range of travel to the other, thus covering the entire frequency range of the receiver.

When it is desired to pre-set any one of stops 37 so that a given broadcasting station will be received when this stop comes into alignment with the member 38 on the yoke 27, the knob 41 is rotated to bring about the desired alignment of the stop 37 to be adjusted and the member 38. When this is accomplished the knob 41 is drawn outwardly causing the conical cam 11 to shift the idler gear shaft 61 to the left against its biasing spring 61'. The tuning knob 64 is then coupled to the stop pinion so that upon rotation of the knob the stop may be moved in longitudinal direction until a desired station is tuned in, whereupon the knob 41 may be pressed inwardly, disconnecting the gear drive from the tuning knob and preserving the new position of adjustment for the stop. This operation may be performed for any one of the stops 37. This entirely novel method of pre-setting the means for selecting a desired station at will is, as pointed out above, an important feature of this aspect of the invention.

45 The antenna coupling circuit 7 referred to above will now be described in greater detail with reference to Figures 1 and 5 of the drawings. As the elements shown in Figure 5 are present in Figure 1, the same reference characters will be 50 used for both figures. The rod antenna 6 of Figure 1 is shown in Figure 5 as being equivalent to a signal source 104 and a capacity 106 in series, this combination of circuit elements being shunted by a capacity 10. The rectangle 6' encloses 55 this equivalent circuit. The capacity 10 of the equivalent antenna circuit just described corresponds to the trimmer condenser 10 of Figure 1 and forms one element of a tunable circuit 108 including the tunable inductance 8, which is 60 effectively in series with the capacity 109. Tuning of inductance 8 and therefore of the tunable circuit 108 is preferably accomplished by a movable core in the manner set forth in the description of Figure 1. A second tunable circuit 111 65 comprising the capacity 112, the previously described coil 9 and the common capacity 109 is coupled to the circuit 108 by the common capacity 109. The capacity 112 is preferably made adjustable so that the resonant frequency of the 70 tunable circuit 111 may be adjusted within close limits when using a coil 9 which, by reason of manufacturing tolerances, departs from previously determined design characteristics.

Because of the high impedance signal source, shown as the rod antenna in Figure 1, high in-

ductance is necessary for coils 8 and 9. And, for effective coverage of a sufficiently large frequency band, the coils 8 and 9 are preferably long and have a relatively small diameter. In this way the average coupling from one turn to another is low when the tuning cores 23 are withdrawn. Small wire for the coils 8 and 9 is preferable to obtain sufficient turns in a given length of coil. This results in a low reactance to resistance ratio, which expression is termed the "Q" of the coil. This relatively low value of Q would, if occurring in known antenna tuning circuits, result in inferior discrimination or station selectivity. When employing coils of the type just described having a value of Q, which may be lower than that of coils designed for capacitive tuned receivers, in the coupling and tuning circuits of the present invention, excellent selectivity and noise discrimination results. Also, material and assembly costs of the coils will be relatively lower as solid wire may be used for winding the coils and cheaper shielding may be used.

The signal input voltage received from the antenna is transferred by the tuned circuits 108 and 111 and appears substantially undiminished in magnitude across the terminals of the capacity 112. This desired and useful signal voltage may be impressed between the anode and grid of a radio frequency amplifier, for example, amplifier 14 of Figure 1, or it may be utilized in any manner known to the art. In practicing this invention, it has been found that a standard radio receiver equipped with the antenna coupling circuit of this invention gave twice as good a signal to noise ratio at 600 kc. as the same set with a high Q coil and a known coupling arrangement.

In the embodiment disclosed by Figure 1 of the drawings, the antenna coupling arrangement of the invention transfers signal energy to the previously mentioned radio frequency amplifier 14 which may be of conventional design. The output circuit of the amplifier 14 is untuned, the principal circuit element thereof being the resistor 114 which cooperates in the usual manner with the blocking and coupling condenser 118 feeding the mixer grid. The resistor 114 together with the radio frequency choke 117, the inductance 118 and capacity 119 provides means to pass a band of frequencies of desired width so that the radio apparatus may be tuned over this band with uniform response if desired, or with greater sensitivity for predetermined portions of the band. The condenser 119 is shown as being adjustable, but is set once to obtain maximum attenuation of signals having frequencies in the neighborhood of the intermediate frequency.

In the following description of the operation of the receiver of Figure 1, which embodies the novel antenna coupling circuit of Figure 5, the theory of signal energy transfer and discrimination against unwanted signals by means of coupled circuits as it applies to this aspect of the invention will be briefly reviewed. Discrimination in any antenna tuning circuit must be sufficient, for obvious reasons, to prevent strong undesired signals from being passed along to the amplifier or amplifiers and this is especially important in a super-heterodyne receiver where undesired signals reaching the converter grid can produce many spurious responses since the converter acts as a mixer. Cascade tuned circuits or R. F. tuned circuits will provide the necessary discrimination. However, efficient coupling must be provided between the cascaded circuits. The circuits described in connection with Figures 1 and 75

4 fulfill this condition of maximum transfer of signal energy, this transfer being efficiently obtained as circuits 108 and 111 can be resonated to the desired signal frequency, and the circuits 5 are readily adjustable or may be adjusted initially to provide optimum coupling.

In this connection it is to be noted that the inductance of the related coils is simultaneously varied and applications for this may be found in 10 circuit details where it is desired to resonate two circuits to the same frequency, to frequencies which must be maintained in fixed ratio to each other or to frequencies which must be separated by a fixed amount. The frequencies may be 15 varied over a wide range while maintaining a desired fixed relationship between them.

The common capacitative coupling provided by capacity 109 discriminates particularly against undesired high frequencies since the reactance 20 decreases as the frequency increases and, therefore, the voltage appearing across the terminals of the condenser 112 decreases as the frequency increases. An additional advantage of the antenna coupling circuit provided by this invention 25 also flows from this. Most disturbances, such as ignition noises from an internal combustion engine, are of high frequency, and two sections of a pi filter are provided by the circuit 7 of the invention to attenuate these disturbances which 30 heretofore have been very troublesome. The first of these filter sections includes the inductance 8, the inherent capacity 106 of the antenna plus capacity 10 and the capacity 109. The second filter section comprises the condenser 109, 35 the inductance 9 and the capacity 112. Because of the greatly improved selectivity, and in particular because of high attenuation of signals in the image range, it is possible to simplify and reduce the cost of circuit elements which follow, 40 at the same time maintaining their efficiency. The antenna system described above permits commercially satisfactory image ratios to be secured when an untuned radio frequency stage, such as is provided at 114 and its associated parts in Figure 1 described above, are employed.

45 Figures 6 to 10 of the drawings disclose a modified form of tuner control which provides a ready means for tuning a radio receiver of any kind by manipulation of controls located in any suitable or convenient position on the receiver or by 50 means of a remote control device preferably of the type disclosed in the co-pending application of E. F. McDonald, Jr., Serial No. 347,516, filed July 25, 1940, and bearing the title Radio control system. It will be understood, however, that any 55 simple type of circuit controller or switch may be used to effect operation of the tuning device from a remote point, and that a plurality of switches located at a number of conveniently accessible points may be employed. Each switch 60 of the plurality of switches may serve to control the tuning mechanism independently of or in conjunction with one or more of the remaining switches.

65 The tuning control mechanism of Figures 6 to 10 indicated by reference character 21' includes features of the mechanism 21 of Figure 1, and, therefore, the similarity existing between these 70 embodiments of the invention will be pointed out as the description proceeds. The receiver may be of any conventional type, such as is shown diagrammatically in Figure 1, but as illustrated by Figures 6, 7, and 10, the tuning device is designed for embodiment in a compact auto radio receiver 122, the general features of which are

illustrated in Figures 6 and 7 of the drawings. Figure 11 also indicates diagrammatically the position of the remote control device mentioned above, which is positioned for actuation by the foot of the driver of the automobile.

The plurality of tunable inductances 124 (Fig. 6) corresponding in function to inductances 8, 9 and 11 of Figure 1, are tunable by plungers 126 of ferrous material, resiliently secured at 130 to a yoke member 127 which is slidably mounted on a reduced portion 128 of a solenoid core 129. The shoulder 131 provided at the end of the solenoid limits slidable movement of the yoke 127 on the portion 128 against which it is moved by the thrust of a compression spring 132A which reacts against an abutment provided by the cap 133. The solenoid 130 slidably receives the core 129 and is provided at one end with a buffer member 132 of rubber or other resilient material which cushions the slidable yoke 127. A spring 134 serves to move the yoke 127 to the right as viewed in Figure 6 and also performs the function of maintaining the yoke member in a position determined by one of a plurality of stops or abutments 136, there being six of these stops in the modification shown in Figures 6 to 10. However, it will be understood that a greater or lesser number of these stops may be provided depending upon the number of stations which are to be selected automatically.

Each of the stops 136 is provided with an internally threaded aperture in which is received, in threaded engagement, an externally threaded rod 131. These rods, six in number, are rotatably carried by a pair of disc members 138 and 139 secured against the ends of an enlarged hexagonal portion 141 of a shaft 142. It will be understood that the enlargement 141 will have as many sides as there are stops 136, or that it may be of any configuration in cross section to prevent rotation of the stops. The shaft 142 is rotatably supported by bearing members 143 and 144 which, for the sake of cheapness of manufacture, may be struck up from a mounting plate 146.

Each rod 137 projects through the plate or disc 139 and is formed as indicated in Figure 6 to provide a driving connection with a pinion 148. One of these pinions 149, is of larger pitch diameter than the remainder for a reason to be described.

It will be apparent from the drawings taken with the foregoing description that the stops will be moved longitudinally between the limits defined by the plates 138 and 139 to position the stops for abutting engagement with the yoke 127 upon rotation of pinions 148 or the larger pinion 149.

A step by step movement of rotation is imparted to the shaft 142 by a self-locking ratchet, details of which are best shown by Figures 8 and 9 of the drawings. Referring to these figures the ratchet mechanism 151 comprises a ratchet wheel 152, provided with teeth 153, there being one tooth for each of the stops 136. A pawl 154 is connected at 156 to a plate 157, the latter being slidably mounted on a supporting web member 158 by means of a flange 160, which is struck outwardly to contact the edge of the plate. This web member may, for convenience, be attached to or form part of the previously mentioned mounting plate 146. The plate fits over the shaft 142 and is provided with an elongated aperture 159, which permits it to slide laterally to an extent necessary to allow

the pawl 154 to step the ratchet wheel a distance of one tooth. Stop members 161 and 162 carried by the plate 157 secure positive locking of the wheel 152 in the following manner:

5 Assuming the ratchet parts to be in the position illustrated by Figure 8 of the drawings, then to bring the next successive stop 136 into position, the plate 157 is moved to the left as viewed in Figure 8, or upwardly as in Figure 6, 10 by a bell crank 163 means to be described, which causes the pawl 154 to engage the ratchet tooth at position 153A, thereby turning the ratchet wheel 152 since the stop 162 will have moved out of interfering engagement with the tooth shown at position 153B. When the plate completes its movement to the left the stop 161 engages in back of the tooth at position 153C, as shown by the dot-dash lines, and this together with a detent member 167, secured to the plate 146, holds the tooth at position 153C in a positive manner. 20 As the plate 157 is returned toward the right under the influence of a spring 166 (Fig. 6), the pawl 154 (Fig. 8) rides over the top of the tooth 153, which has just been moved to the position 153A, holding the tooth now at position 153C against the detent member 167 until stop member 162 is in place behind the tooth now at position 153B.

The plate 157 is reciprocated in the manner 30 just described to turn the shaft 142 by the previously mentioned bell crank member 163 (Fig. 6) pivoted at 168 to a bracket 169 secured on the casing of the solenoid 130. One arm 171 of the bell crank is pivotally connected at 172 to the ratchet plate 157 and the remaining arm 173 is provided with a member 174, preferably of brass or other non-magnetic material, which projects into the bore of the solenoid 130 so as to be engaged by the core 129 as it approaches the end of its stroke.

40 A knob or handle member 176, conveniently formed to be grasped and rotated, is secured upon a hollow rod or shaft 177, an end of which extends exteriorly of the casing or panel of the radio receiver. The hollow rod 177 is rotatably journalized in suitable bearings which permit it to be moved longitudinally, and it carries on its end a crown gear 178. This gear is adapted to mesh with and drive the pinions 148, or the large pinion 149. When the handle 176 is in the position 50 illustrated in Figure 6 of the drawings, the gear 178 is in mesh with the large pinion 149, so that the stop 136 may be shifted from one limit of travel to the other to adjust the inductance of the coils throughout their range from one extreme value to the other. This provides for rapid manual tuning of the receiver by turning the knob 176.

An extended portion 181 of the shaft 142 is 60 provided with a radially projecting pin 182, position for engagement with a member 183 projecting from the hollow shaft 177. As the shaft 142 is rotated so that the pinion 149 occupies the position illustrated by Figure 6 of the drawings, the pin 182 will engage the member 183, thus moving the crown gear 178 inwardly or upwardly as viewed in Figure 6 to a position for meshing engagement with the pinion 149. A spring 65 pressed detent 184 engages the member 183 to hold the shaft 177 in the longitudinal position in which it is placed, insuring unobstructed meshing engagement of the gear 178 and the large pinion 149.

70 When the shaft 142 is rotated by the ratchet 151 to any position except that shown in Figure

6 of the drawings, the crown gear 178 must be manually moved by drawing the knob 176 outwardly into position to mesh effectively with the small pinions 148. When the shaft 142 and the assembly carrying the stops 136 approach the position occupied in Figure 6 of the drawings, the pin 182 will engage the member 183 and automatically cause the crown gear 178 to be moved inwardly so that it will not interfere with movement of the pinion 149 into position.

Energization of the solenoid 130 to select, by means of the stops 136, pre-set stations in succession is accomplished by a switch 185 (Fig. 11), the contact members of which are operated by a rod member 186 projecting through a bore in the control shaft 177 in a manner to provide an exteriorly projecting push button portion 187. Figure 6 illustrates a modification of the switch 185 omitting the muting contact to be described in connection with Figure 11 of the drawings.

While the knob 176 and button 187 have been described as projecting exteriorly of the casing or panel of the receiver in which the tuning and station selecting device is used, it will be understood that these or other control means which may be provided may be extended to any convenient point or may be connected to any suitable type of mechanism for extending the operating distance.

The switch 185 of Figure 11 comprises a muting contact 188, a control contact 189 for connection to the solenoid 130 and a grounded contact 191. The remaining terminal of solenoid 130 is connected to a suitable power source 192, which in conventional practice may be the storage battery of an automobile having one of its terminals connected to ground as at 193. The battery 192 may be employed to energize the circuits of the receiver 122 over a conductor 194. If desired, the conductor 194 may include a switch 195 so as to obtain operation of the control mechanism independently of the receiver.

The connection 196 from the solenoid to the battery may include the movable contact 197 of a main switch and, also, an ignition, or other control switch 198 for the automobile, if desired.

The muting contact 188 is connected to one side of the voice coil 199 of the receiver sound reproducer so that upon pressing the button 187 the contact 188 will be grounded by the contact 191 to silence the receiver. When sufficient pressure is exerted upon the button 187 to overcome the resilient pressure of both contacts 188 and 191 so as to cause engagement of the latter with 189, the solenoid 130 will be energized, provided switches 197 and 198 are closed, to withdraw the yoke 127 and rotate the stop assembly to bring the next stop in succession into position for engagement by the yoke. This action will occur upon each operation of the button 187 causing closure of contacts 188 and 191. The stop assembly will be advanced one step for each complete operation of the button 187, thereby progressively tuning in all of the pre-set stations. When the stop assembly reaches the position illustrated by Figure 6 of the drawings, the receiver may be manually tuned throughout its operating range by turning the knob 176.

When desired, a foot control may be provided as pointed out above by the addition of a switch 201 corresponding to the switch 64 of the above noted co-pending application. A connection from the terminal of the solenoid coil is made to the stationary contact 202 of the foot actuated con-

trol switch 201 which is mounted upon the floor board 203 of the automobile. The switch 201 also has a movable member 204 connected to ground as at 206. The switch 201 has a muting contact 207 connected to one terminal of the voice coil 199 of the reproducer. The muting contact 207 of the switch 201 is positioned to be engaged by the movable member 204 prior to engagement between the movable member 204 and the control contact 202. Thus, initial movement of member 204 of the switch 201 short circuits the voice coil 199 to mute the radio set. This muting system is similar to that disclosed in the McDonald application mentioned above.

10 A plurality of switches may be positioned in any of the passenger compartments of the car, or a plurality of controlling switches in parallel may be employed in the manner set forth in the co-pending application.

15 The several positions of the shaft 142, which are obtained by repeatedly operating the button 187, are indicated by a drum 211 (Fig. 6). This drum bears suitable indicia, such as the numerals 1 to 5 indicated by reference character 212 and the letter "D", the latter indicating the manual or dial tuning position of the stop assembly.

20 A portion of the drum 211 is visible through an aperture 214 (Fig. 10) in the casing or panel 215 of the receiver 122. As Figure 6 of the drawings shows the mechanism in the "dial" or manual tuning position, Figure 10 indicates that the letter "D" is visible through the aperture 214.

25 The panel 215 of the receiver is provided with a scale 216 graduated in kilocycles or other suitable units, as indicated by the scale divisions 217. A pointer 218 (Figure 6) operated from the yoke member 127 cooperates with the scale 216 and thereby serves to indicate the position of the cores 126 with respect to their respective inductances. To operate the pointer from the yoke a member 219 is secured on the yoke and has a pivotal connection at 221 to the pointer at a point between its ends. One end of the pointer is slotted as indicated at 222, the slot accommodating a stationary pin 224. Figure 6 illustrates the pointer at one end of the scale and as the yoke moves to the right the slotted end 222 of the pointer will move inwardly over the pin 224, thereby flattening the path of travel of the indicating end of the pointer so that the scale 216 projects outwardly only a relatively small distance from the panel 215 of the receiver.

30 Figures 12 and 13 of the drawings disclose another modification of the tuner control of this invention which provides a ready means for tuning a radio receiver to preset stations by manipulation of any type of multiple contact switch. The tuning control mechanism indicated by reference character 230 is or may be similar to the stop mechanisms already described in connection with the Figures 1 to 6 of the drawings. The receiver as before may be of any conventional type, such as is shown diagrammatically in Figure 1. It will be understood that the assembly 230 positions tuning members 231 which cooperate with tunable inductances in the manner of Figures 1 or 6. These tuning members 231 are carried by a bar member indicated at 232, which is secured upon a rod 233 connected to a solenoid core 234. The rod 233 may have its forward end 235 bent to cooperate with a plurality of stops or abutments 236 of the assembly 230, adjustably carried by the turret member 237. A member 238 fixed to the end 235 of the rod 233 serves as an

abutment for a spring 241 which cushions a buffer 241' carried by the end of the rod.

The turret member 237 is secured upon a shaft 243 which also carries a ratchet wheel 244 engageable by a pawl 246 so as to rotate the shaft 243 one step for each operation of the pawl. The pawl 246 is pivoted to an arm 247, which swings about the shaft 243 and is pivotally slidably connected to one arm of a bell crank 248 having its other arm pivotally and slidably connected to a lever member 249 the latter being pivoted on a fixed bearing member 251. The lever member 249 extends from the pivot point 251 and is slotted at 252 to accommodate a pin 253 secured upon the rod 233. The upper end of the lever 249 is preferably positioned so as to be visible and cooperates with a scale 254 having suitable graduations thereon.

A manually operable switch 256 shown as a simple multiple contact switch, has a series of stationary contacts 257 cooperating with a series of movable contacts 258 to successively break contact between the stationary contacts 257 and the movable contacts 258. The switch 256 is so arranged that when the switch knob 259 (Figure 13) is turned to one of the positions indicated by the indicia 261, the movable contact 258 corresponding to that setting of the switch will be opened, for example, by member 262 on the switch operator 259. The stationary contacts 257 are connected to a suitable power source such as the battery 263, the remaining terminal of this battery being connected by way of a switch 264 to one terminal of the solenoid 266. The remaining terminal of the solenoid 266 is connected to a rotary switch 267 shown as being operated mechanically from the shaft 243 by a pinion 268 and a gear 269 on the switch shaft 271. The switch 267 comprises a rotary member 272 on the shaft 271 which is provided with oppositely disposed contacts 273 and 274. One or the other of these contacts moves over a set of stationary contacts 276, one of which is provided for each of the movable contacts 258 of the switch 256.

By reason of the gear reduction provided by gear 269 and pinion 268, contacts 273 or 274 move over the contacts 276.

In operation of the modification just described the manually operable switch member 259 (Figure 13), which serves as a tuning dial, is moved to any position at which a pre-set station will be received. For example, as shown in Figures 12 and 13 the turret operating mechanism 230 is in position corresponding to the position marked 4 on the switch 256, then when the switch handle 259 is moved to position 1 as shown in Figure 13 of the drawings the solenoid 266 will be energized by reason of engagement of contact 274 with the stationary contact 276 corresponding to closed contacts 258 and 257 at position No. 4 of the switch 256. This will cause energization of the solenoid to withdraw the member 233 to the left to the position shown moving the cores 231 in a manner explained previously. This movement of the solenoid core 234 also compresses the spring 241. Also, the switch 264 will be opened by an extension 277 on the core 234. The energy stored in the compression spring 241 will move the member 233 to the right rocking the lever 249 by reason of its connection at 252. This will move the pawl 246 by means of the bell crank 248, a distance of one tooth, thereby moving the turret 237 one step to place the next successive stop 236 in the path of movement of

the member 235. This operation will be repeated until contact 273 engages the contact 276 associated with the open contacts 258 and 257 corresponding to position 2 of the switch 259. That is to say the solenoid is energized, whenever the rod 233 is in its rightmost position and a circuit is completed through the switches 267 and 256, to move the rod 233 to the left. The switch 264 then breaks the solenoid circuit to permit the rod 233 to be returned to the right by the spring 241 and this operation is repeated until the position of the switch 267 corresponds to the position of switch 256. The stops 236 in the turret 237 are, it will be understood, provided with pinions 278 in the manner already described in connection with Figure 1 of the drawings. These pinions 278 cooperate with a gear 279 which is driven by a gear 281. When the switch operator 259 is placed in the manual position indicated by the letter M the pinion 278 for the stop 236 corresponding to that position is brought into mesh with the gear 279. At other positions of the turret 237 means may be provided as disclosed in Figure 1 of the drawings to bring the gear 279 into mesh with the pinion 278 brought to a position adjacent to that gear to provide for pre-setting the stop to select a different station.

Figures 14 to 18 of the drawings disclose another modification of the tuner control mechanism of this invention. This modification, indicated generally by the reference character 151', includes features of the mechanism 21 of Figure 1, and, therefore, the similarity existing between these embodiments of the invention will be pointed out as the description proceeds. The receiver 152', like the receiver of Figure 1 may be of any conventional type, but as illustrated in Figure 14, the tuning mechanism is designed for tuning an auto radio receiver, the compact outlines of which are shown in Figures 14 and 15 of the drawings. The receiver and tuning mechanism are enclosed by a casing 153'. Figure 19 shows the electrical features of the mechanism 151' and also indicates diagrammatically the position of a foot operated switch 154', which is or may be similar to the foot control pedal 204 of Figure 11.

The plurality of tunable inductances in the form of coils 156', 157' and 158', corresponding in function to the inductances 8, 9 and 17 of Figure 1, are tunable by three cores 159' of low loss material. These cores are individually secured to a yoke member 161' of sheet metal or other suitable light weight material by insulating members 162'. As was pointed out in connection with Figures 6 to 11 of the drawings, circuit control or adjusting devices of many kinds may be connected to the yoke member 161' or its equivalent. Each member 162' is grooved as indicated at 163', so that it will be retained in an aperture in the yoke member 161'. Each core 159' is provided with a threaded stem 164', which is received in a nut 166' embedded in the member 162'.

The coils 156', 157' and 158' are wound on tubular members 167', each tubular member being held in position on a metallic shield 168' by an opening in an insulating bushing member 169' and a plug member 171'. The plug member 171' for the coil 156' serves to clamp the tubular member, the shield and a mounting plate 172' to a supporting bracket by means of a screw 174' engaged in a threaded bore in the plug. The remaining two coil assemblies are secured directly to the plate 172' by their plugs 171' and screws 174'. Each coil is surrounded by a tubular member 176' of high permeability magnetic mate-

rial which is positioned between the insulating bushing member 169' and a bushing 177' at the base of the shield.

The yoke member 161' is secured to the end of a solenoid core 178' by suitable fastening means 179' (Figure 15). A solenoid 181', which slidably receives the core 178', comprises a magnetic frame 182' supported on a sheet metal platform or the like 183'. A U-shaped member 184' of non-magnetic material is suitably secured to the magnetic frame 182' of the solenoid. The core 178' projects through an aperture in the non-magnetic member 184', providing a longitudinal space to accommodate a ratchet operating plate 186' and a sleeve-like hub 187' thereon. A buffer member in the form of a soft, resilient washer 188' is interposed between the yoke 161' and the member 184'. A spring 189' serves to move the yoke 161' to the right, as viewed in Figure 14, and also performs the function of maintaining the yoke in a position determined by one of a plurality of stops or abutments 190' and an additional stop or abutment 190a. The number of these stops may vary, depending on the number of positions of the yoke 161' or its equivalent, which are to be selected automatically.

Rotation of the yoke member 161' is prevented by guide rods 191' secured to a member 192' carried by the previously mentioned support or shelf 183'. One of the apertures 193' which receives the lower guide rod 191' may be elongated, as shown in Figure 15, to provide for slight errors in locating the rods 191' in the frame 192'.

Each of the stops 190' is provided with an internally threaded aperture in which is received an externally threaded rod 194'. The stop member 190a is longitudinally moved by a rod 194a provided with threads of longer pitch than the rod 194'. The stops are split as at 196' (Figure 15) to provide frictional clamping engagement with the threaded rods. The rods 194' and the rod 194a are rotatably supported in flanges 198' and 199' formed integrally with or secured upon a shaft 200'. A hexagonal portion 201' of this shaft prevents rotation of the stops while permitting them to move longitudinally of the shaft. The shaft portion 201' may be of any desired configuration in cross section designed to prevent rotation of the stops. The shaft 200' is supported in bearing members 202' and 203' suitably secured to the support 183'. Each of the rods 194' projects through the flange 199' and has secured thereon a pinion 206'. The rod 194a is provided in this manner with an enlarged pinion 206a for a purpose to be described later.

The bearing flanges 198' and 199' and the parts carried thereby constitute a turret assembly 207' which is rotated angularly one-sixth of a turn, in the embodiment of Figure 14, by a ratchet mechanism comprising a ratchet wheel 208' (Figures 14 and 16) having angularly spaced teeth 209'. The angular spacing of the teeth 209' is equal to the angular spacing of the stops 190' on the turret assembly. Step by step movement is imparted to the wheel 208' by a pawl member 211' (Figure 16) carried by the previously mentioned operating plate 186'. Helical cam slots 212' in the hub 187' secured to the plate 186' receive a pin 214', which is secured to the solenoid core 178'. The ratchet plate 186' is retained in the full line position of Figure 16 by means of a spring 216'. The plate 186' is swung to its dotted line position by the pin 214' sliding in the cam slots 212'. The tendency of the core 178' to rotate is prevented by the guide rods 191'.

The ratchet wheel 208' is held securely against accidental rotation by a member 217', engaged with the back of the ratchet tooth at the position 209a. The member 217' is mounted on the magnetic frame structure 182' of the solenoid. An upturned ear 219' on the plate 186', engaged in front of the tooth at the position 209a, prevents rotation of the ratchet wheel 208' in a forward direction. An additional stop for this purpose is provided by the upturned ear 221' which is engaged in front of another tooth adjacent the one at position 209a. The pawl 211' has a slightly inclined end 222' (Figure 16) which permits it to pass over the tooth at position 209b as the plate approaches its dotted line position. The end 224' (Figure 14) of the slot 226' in the pawl will engage behind the tooth at position 109b as the plate returns to its full line position.

When the solenoid 181' is energized under the control of a switch in a manner to be described, the pin 214' enters the cam slot 212' and rotates the plate 186' to its dotted line position in Figure 16. During this movement, the end 222' of the pawl 211' passes over the front of the ratchet tooth at position 209b to engage the end 224' of the slot 226' behind the tooth. When the solenoid 181' is deenergized, the core 178' moves to the right as viewed in Figure 14 under the influence of the spring 189' and returns the plate 186' to its full line position, thereby advancing the turret assembly one step to bring the next successive stop 190' into position to arrest the return movement of the yoke 161'.

The stops 190' and 190a are adjusted longitudinally of the turret assembly by a crown gear 227' secured on or integral with a hollow shaft 228'.

This hollow shaft is provided at or adjacent its end with a knob member 229' and is journaled in bearing members 231' and 232'. The bearing member 231' is secured to an upstanding portion 233' of a plate member 234' (Figure 17). This supporting plate member is secured by suitable fastening means 236' to the supporting shelf 183'. The bearing member 232' (Figures 14 and 17) is in the form of a disc which is retained in its initial dished shape by being confined at its circumference in a groove 237' provided by an annular recess in an annular member 238'. The annular member 238' is secured against an upturned portion 239' of the supporting member 234'. The shaft 228' is retained in its bearing aperture in the disc 232' by means of a snap ring 241' seated in a groove at the end of the shaft 228'. The previously mentioned crown gear 227' is secured on the shaft 228' at a point such that it will be in mesh with the pinion 206a when the turret assembly is in the position shown by Figure 14. With the turret in any other position, the gear 227' may be brought into mesh with a pinion 206' by grasping the knob and pulling it outwardly to the position indicated by the dotted lines of Figure 17. The shaft and gear are maintained in this position by the snap action of the disc 232'. The disc 232' maintains the shaft 228' firmly in either position without interfering with its freedom of rotation. With the knob 229' in its dotted line position, any one of the stops 190' may be moved longitudinally by turning the knob 229'. Operation of the ratchet mechanism by the solenoid 181' is prevented at this time since the operating circuit of the solenoid is opened at the switch contacts 242', one of which is engaged by the insulating sleeve 244' as shown by the dotted lines in Figure 17.

Energization of the solenoid 181' to select preset stations in succession is accomplished by the switch 246' (Figures 14, 17, and 19), the contact members of which are operated by a rod member 247' projecting through a bore in the control shaft 228'. A push button 248' is provided at the end of the rod 247'. The rod and button are retained in position in the hollow shaft by a shoulder 249' on the knob 229'. The knob 229' is concave as indicated by reference character 251' to assist in locating the button 248' by touch. 10

Figure 19 of the drawings illustrates diagrammatically the electric circuit connections of the solenoid and controlling switch 246'. The switch 246', shown in greater detail in Figure 17, comprises a grounded contact spring member 253' secured to sheet 254' of insulating material, the latter being secured to the underside of the shelf 183' by suitable fastening means, such as the previously mentioned rivets 236'. The contact spring member 253' is provided with contacts 255' and 256' (Figure 14) which are adapted to engage, respectively, a muting contact 258' and a control contact 259'. These last named contacts are carried by contact springs secured to the insulating plate 254', thereby to be insulated from the grounded parts of the tuning mechanism. The muting contact 258' is connected to one side of the voice coil of a sound reproducer 262' so that upon exerting moderate pressure on the button 248' the contact 255' will engage the contact 258' to short circuit the voice coil of the reproducer and silence the receiver. When sufficient pressure is exerted upon the button 248' to overcome the resilient action of the contact spring 243' and the spring supporting the contact 258', the contact 256' will engage the control contact 259'. A circuit is thereby completed to energize the solenoid 181' from ground at 264', the contacts 256' and 259', the switch 242', the conductor 266', the solenoid 181', a receiver power switch 267', and a power source shown as the battery 268'. Upon completion of the circuit just described the yoke member 161' will be 40 drawn to the left as viewed in Figure 14 against the tension of the spring 189'. The pin 214' will enter the cam slots 212' during movement of the solenoid core to thereby rotate the ratchet plate 186' to bring the pawl 211' into operative engagement with a tooth on the ratchet wheel 208' in the manner described above. When the button 248' is released, the solenoid core will be moved or returned to the right by the spring 189', causing the ratchet pawl 211' to rotate the turret to bring the next successive stop 190' into position for engagement by the yoke 161' to tune in a station automatically. The turret assembly will be advanced one step for each operation of the button 248', thereby progressively to tune in all of the preset stations. 50

When desired, any one of the stops 190' may be preset to position the yoke member 161' to tune in a given station by drawing the knob 229' outwardly, bringing the gear 227' into mesh with the pinion 206' associated with the stop selected for adjustment. The snap disc 232' snaps to its reversed concave shape and holds the gear 227' in mesh with the pinion 206' without, however, interfering with the freedom of rotation of the gear. The knob 229' may now be rotated to turn the threaded rod 194' associated with the stop 190' selected for adjustment until satisfactory reception of the desired station is obtained. When this is accomplished, the knob 229' may 75

be pushed inwardly to disengage the crown gear 227' from the pinion 206', the snap disc 232' again assuming its initial configuration. Inadvertent operation of the tuning mechanism at any time during the setting of a stop 190' by operating the switches 246' or 269' is prevented by reason of the contacts of the switch 242' being retained in circuit opening position by the insulating sleeve 244' when the shaft 228' is in the dotted line position indicated on Figure 17. 10

The parts including the hollow shaft 228' and the contact operating rod 247' may be proportioned so that the switch 246' is inoperative to close the contacts 256' and 259' when the shaft 228' is drawn outwardly. These parts may also be proportioned so that only the muting contact may be engaged when the hollow shaft is withdrawn to preset one of the stops. The muting contact (described below) of the foot switch 154' is preferably available at all times. 15

A connection is made from the terminal of the solenoid 181' to the stationary contact 270' of the foot switch 154' by way of the switch 242' and the conductors 266' and 272'. The switch 154' also has a muting contact 273' connected to the voice coil of the reproducer 262' by way of the conductor 274' to accomplish muting of the receiver by grounding contact 273' by the grounded movable contact 269'. The switch 154' is operated in the same manner as the switch 201 of Figure 11. Initial movement of the member 269' silences the receiver and further movement thereof selects the next successive stop 190' to thereby select a preset station. This operation may be repeated to select the preset stations successively. 20

In certain installations it may be desired to ground the contact member 269' on a metallic portion of the tuning device 151' or its associated apparatus, for example, the receiver 152'. To accomplish this and to provide for a convenient and readily detachable connection of the foot switch to the tuning apparatus 151', a socket or receptacle 278' is secured in an aperture in the receiver casing 153' (Figures 14, 20 and 21) by suitable fastening means 280'. The contact 281' of the receptacle 278' is connected to ground and is adapted to engage a contact prong 283' on the plug 284' which is connected to the metallic shell 286' of the plug and in turn to the metallic sheath 287' of the cable 288'. The remaining contacts 289' and 291' of the receptacle 278' are connected to the conductors 272' and 274' (Figures 19 and 20) which connect to the switch 242' and the voice coil of the reproducer 262', respectively. An annulus 292', forming part of the receptacle 278', is provided with annularly disposed spring fingers 293' which frictionally engage the metallic shell 286' which surrounds the body of the plug 284'. The conductors within the cable 288' are suitably connected to the contacts within the switch 154', and the cable sheath 287' is or may be connected to the body or casing of the switch 154' which may in turn be connected to the contact 269'. The indicator drum 299', similar to the drum 131' of Figure 2 of the drawings, is provided to indicate the several positions of the shaft 200'. The drum 299' bears numerals 1 to 5 indicated by the reference character 300' and the letter "D" to indicate the manual or tuning position with the stop 190a in engagement with the yoke 161'. A portion of the drum is visible through an aperture 301' in the casing 153'. 55

An arcuate scale plate 302' is secured to the

face of the casing 153' to cooperate with a pointer 303'. The pointer 303' is pivotally connected to a bracket member 304' (Figure 15), which is secured to the yoke 161' by suitable fastening means as the screw 306'. Displacement of the bracket is prevented by a tang 307' which is engaged in an aperture in the yoke 161'. The end of the pointer 303' is provided with a slot 308' (Figure 14) to engage a pin 309' secured to a stationary portion of the mechanism. When the cores 159' are fully inserted in their corresponding inductances, the pointer 303' is at one end of the scale to indicate that the receiver is tuned to one extreme end of its range.

It will be seen from the foregoing description that control apparatus embodying the present invention is capable of use in a wide variety of control equipment and may be readily and cheaply constructed without resorting to delicate and costly machine work in the manufacture of the parts. Accurate fitting operations during assembly of the parts constituting a control device embodying this invention are not necessary. Radio apparatus embodying the present invention is convenient to use and may be compactly constructed. It is capable of being accurately tuned by the simple operation of pressing a button, manipulating a simple switch or operating a foot pedal. This feature of compactness permits radio apparatus embodying the present invention to be installed in vehicles, boats, and aircraft. The tuning and control system of the present invention is particularly applicable to the control of automobile radio sets and has been described in detail with respect to operation from low voltage batteries. However, other types of radio sets, such as sets operated from alternating current or higher voltage direct current may be operated at the set or from a remote point in accordance with the principles of the present invention.

While the invention has been described and explained in detail in connection with several illustrative embodiments thereof, it is to be understood that the invention may be embodied in other forms, and, therefore, the invention is not limited except as indicated by the terms and scope of the appended claims.

What is claimed is:

1. Apparatus for the control of electrical equipment comprising a movable controlling member, an electromagnet for moving said member in one direction, resilient means tending to move said member in the opposite direction, a stop assembly comprising spaced stops, means on said movable member for cooperation with said stop assembly, means to bring about cooperation of said stops with said member in a predetermined order, switch means, an electrical circuit including said switch means for energizing said electromagnet whereby to move said member upon operation of said switch means, and means for operating said switch means to effect control of said equipment.

2. Apparatus for the control of electrical equipment comprising a movable controlling member, an electromagnet for moving said member in one direction, resilient means tending to move said member in the opposite direction, a movable stop assembly comprising spaced stops, means operably connected to said electromagnet to move said stop assembly successively to position said stops for cooperation with said movable member, switch means, an electrical circuit including said switch means for energizing said electro-

magnet whereby to move said member upon operation of said switch means, and means for operating said switch means for energizing said electromagnet.

- 5 3. In apparatus for the control of electrical equipment, movable means for effecting control of said equipment upon movement from one extreme end of its range of movement to the other, power means for moving said movable means in one direction throughout its range of movement, a movable abutment in the return path of said movable means, and means for returning said movable means toward said abutment.
- 10 4. In apparatus for the control of electrical equipment, a movable controlling member, power means for moving said member in one direction, resilient means tending to move said member in the opposite direction, a rotatable stop assembly comprising angularly spaced stops, means operably connected to said power means to rotate said stop assembly and thereby successively to position said stops for engagement with said member, and means for controlling the operation of said power means.
- 15 5. In a system for controlling electrical apparatus, a movable control device, means for positioning said control device in a plurality of apparatus controlling positions, said means comprising a plurality of adjustable abutments for cooperation with said movable control device to position the same, electrical means for effecting simultaneous movement of said control device and selecting one of said abutments for cooperation with said control device, and means for adjusting the cooperating position of the one of said abutments selected for cooperation with said control device while engaged with said control device.
- 20 6. Apparatus for the control of electrical equipment comprising a movable control device, an electromagnet for moving said control device in one direction, means tending to move said control device in the opposite direction, a movable stop assembly comprising stops designed to arrest movement of said control device when moving under the influence of said first named means, means operably connected to said electromagnet to move said stop assembly, switch means, an electrical circuit including said switch means and
- 25 50 7. Apparatus for the control of electrical equipment comprising a movable control device, an electromagnet for energizing said electromagnet whereby to move said control device, means for adjusting the abutting position of said stops on said stop assembly, and manually operable means designed for cooperation with said stop adjusting means.
- 30 55 8. Apparatus for the control of electrical equipment comprising a movable control device, an electromagnet for moving said control device in one direction, means tending to move said control device in the opposite direction, a rotatable stop assembly comprising preset stops designed to arrest movement of said control device when moving under the influence of said first named means, means operably connected to said electromagnet to rotate said stop assembly to successively position said stops for cooperation with said control device, switch means comprising a movable member capable of partial or full actuation, an electrical circuit adapted to cause control of said electrical equipment upon partial actuation of said switch member, and an additional electrical circuit including said switch means and said electromagnet for energizing said electromagnet whereby to move said control device upon full actuation of said clutch member.
- 35 60 65 70 75

8. In a control device, a plurality of stop members, each member having a threaded aperture, a plurality of threaded members one for each stop extending through said apertures, spaced supporting members supporting said threaded members adjacent their ends, a shaft carrying said spaced supporting members, and means on said shaft for engagement with said stop members to prevent rotation thereof when said threaded members are rotated to adjust the position of said stop members.

9. A tuner for a radio receiver comprising a movable tuning device, an electromagnet for moving said tuning device in one direction, resilient means tending to move said device in the opposite direction, a stop assembly comprising spaced stops, means on said tuning device for engaging with said stop assembly, means to bring about engagement of said stops with said tuning device in a predetermined order, switch means, and an electrical circuit including said switch means and said electromagnet for energizing said electromagnet whereby to move said tuning device upon operation of said switch means.

10. A tuner for a radio receiver comprising a movable tuning device, an electromagnet for moving said tuning device in one direction, resilient means tending to move said device in the opposite direction, a movable stop assembly comprising spaced stops, means operably connected to said electromagnet to move said stop assembly successively to position said stops for cooperation with said tuning device, switch means, an electrical circuit including said switch means for energizing said electromagnet whereby to move said tuning device upon operation of said switch means, and means for operating said switch means for energizing said electromagnet.

11. In a tuner for radio apparatus, longitudinally movable means for tuning said apparatus from one extreme end of its tuning range to the other, means for moving said tuning means throughout the tuning range of said apparatus comprising a movable abutment engageable with said movable tuning means, means to adjust the position of said abutment while in abutting engagement with said tuning means, means normally urging said tuning means against said abutment, and electrical means for disengaging said tuning means from said abutment.

12. A tuner for radio apparatus comprising means movable to adjust said tuner from one extreme end of the tuning range to the other, a plurality of adjustable abutments for said movable means, means for positioning said abutments successively in the path of movement of said movable tuning means to thereby provide a plurality of preset tuning positions, means individual to each of said abutments comprising a rotatable threaded member in threaded engagement with its associated abutment for adjusting the abutting position of said abutments, a pinion secured to each of said threaded members, and means shiftable for driving engagement with said pinion associated with the one of said abutments positioned to engage said tuning means.

13. The combination of claim 12 wherein one of said rotatable threaded members is threaded to move its associated abutment at an increased speed, whereby said associated abutment is available for rapidly moving said tuning means from one end of its range to the other to provide continuous dial tuning of said apparatus.

14. The combination of claim 12 wherein one of said rotatable members is provided with means for causing its associated abutment to traverse its range of movement at an increased speed whereby said associated abutment is available for rapidly moving said tuning means from one end of its range to the other to provide continuous rapid tuning of said apparatus.

15. In a tuner for radio apparatus, longitudinally movable means for tuning said apparatus from one extreme end of its range to the other, a plurality of adjustable means for positioning said tuning means at predetermined longitudinally spaced points within the tuning range of said apparatus, means for positioning said plurality of adjustable means successively for cooperation with said first named means, adjusting means individual to each of said adjustable means for adjusting them from one end of the tuning range to the other successively as said adjustable means are positioned successively, and means shiftable to engage the adjusting means when said adjusting means are brought successively into engagement with said tuning means.

16. A tuner for a radio receiver comprising a movable tuning device, an electromagnet for moving said tuning device in one direction, resilient means tending to move said device in the opposite direction, a rotatable stop assembly comprising angularly spaced stops, means operably connected to said electromagnet to rotate said stop assembly successively to position said stops for cooperation with said tuning device, switch means, an electrical circuit including said switch means for energizing said electromagnet whereby to move said tuning device upon operation of said switch means, and means for operating said switch means for energizing said electromagnet.

17. A tuner for a radio receiver comprising a movable tuning device, means tending to move said device in one direction, an electromagnet for moving said tuning device in the opposite direction, a movable stop assembly comprising spaced supporting members, stop members carried by said supporting members, and means operatively connected to said electromagnet to bring about cooperation of said stop members with said tuning device in a predetermined order.

18. A tuner for a radio receiver comprising a movable tuning device, an electromagnet for moving said tuning device in one direction, resilient means tending to move said device in the opposite direction, a movable stop assembly comprising angularly spaced stops, means successively to position said stops for cooperation with said tuning device, said last named means operating in timed relationship with said electromagnet, switch means, an electrical circuit including said switch means and said electromagnet for energizing said electromagnet whereby to move said tuning device upon operation of said switch means, and means comprising a manual control for operating said switch means.

19. A tuner for a radio receiver comprising a movable tuning device, means tending to move said device in one direction, an electromagnet for moving said tuning device in the opposite direction, a rotatable stop assembly comprising supporting members and angularly spaced stop members, and means operatively connected to said electromagnet to impart increments of angular movement to said stop assembly substantially equal to the angular spacing between said stop

members for each operation of said electromagnet, thereby successively to position said stop members for cooperation with said tuning device.

20. A tuner for a radio receiver comprising a movable tuning device, spring means tending to move said device in one direction, an electromagnet for moving said tuning device in the opposite direction, spaced stop means, and means to bring about cooperation of said spaced stop means with said tuning device in a predetermined order.

21. A tuner for a radio receiver comprising a movable tuning device, an electromagnet for moving said tuning device in one direction, means tending to move said device in the opposite direction, a rotatable stop assembly comprising supporting members, angularly spaced adjustable stop members carried by said supporting members, means to impart increments of angular movement to said stop assembly substantially equal to the angular spacing between said stop members, thereby successively to position said stop members for cooperation with said tuning device, and means to adjust a stop member selected for cooperation with said tuning device.

22. A device comprising a plurality of angularly spaced stop means, means associated with said stop means to adjust the position of the latter, means maintaining said stop means in non-rotatable relation relative to said last-mentioned means, means intermittently to rotate said spaced stop means about an axis common to said plurality of angularly spaced stop means, means to cooperate with each of said stop means in turn for adjusting the same when said plurality of stop means is rotated intermittently about said axis to bring each of said stop means in turn into position to cooperate with said adjusting means.

23. A device comprising a plurality of stop members, a plurality of rotatable supporting members, one for each stop member, means associated with said supporting members and said stop members to adjust the position of the latter upon rotation of said supporting members, a pinion carried by each supporting member, spaced members rotatably carrying said supporting members adjacent their ends, means intermittently to rotate said spaced carrying members, means to prevent rotation of said stop members during rotation of said supporting members, a rotatable gear, and means to position said gear to engage one of said pinions upon rotation of said carrying members to select a stop for adjustment.

24. A tuner for a radio receiver comprising a movable tuning device, an electromagnet for moving said tuning device in one direction, means tending to move said device in the opposite direction, a plurality of angularly spaced adjustable stop means, means to impart angular movement to said plurality of said stop means substantially equal to the angular spacing between said stop means for each operation of said electromagnet, thereby successively to position said stop means for cooperation with said tuning device, and means to adjust the one of said stop means selected for cooperation with said tuning device.

25. A device comprising a plurality of stop members, each member having a threaded aperture, a plurality of threaded members, one for each stop member extending through said apertures, spaced supporting members supporting said threaded members adjacent their ends, means intermittently to rotate said spaced supporting members, a shaft carrying said spaced supporting members, means on said shaft for engagement

with said stop members to prevent rotation thereof upon rotation of said threaded members, a pinion secured to each of said threaded members, a rotatable gear, and means to position said gear to engage one of said pinions upon rotation of said supporting members to select a stop for adjustment.

26. A device comprising a plurality of stop members, each member having a threaded aperture, a plurality of threaded members, one for each stop member extending through said apertures, one of said threaded members being provided with a thread of longer pitch than the others, spaced supporting members supporting said threaded members adjacent their ends, means intermittently to rotate said spaced supporting members, a shaft carrying said spaced supporting members, means on said shaft for engagement with said stop members to prevent rotation thereof upon rotation of said threaded members, a pinion secured on each of said threaded members which are provided with threads of the same pitch, a larger pinion secured on said threaded member which is provided with threads of longer pitch, a rotatable gear, means to position said gear to engage a selected one of said pinions as said spaced supporting members are rotated, and means to rotate said gear whereby to adjust the position of the stop member associated with said pinion with which said gear is in meshing engagement.

27. A device comprising a plurality of stop members, each member having a threaded aperture, a plurality of angularly spaced threaded members, one for each stop member extending through said apertures, spaced supporting members supporting said threaded members adjacent their ends, means to rotate said spaced supporting members intermittently through an angular distance substantially equal to the angular spacing of said threaded members, a pinion secured on each of said threaded members, a gear, means to position said gear for meshing engagement with one of said pinions positioned by rotation of said spaced supporting members, means to rotate said gear thereby to move said apertured stop members for adjustment, and means to restore said gear to its normal non-meshing position.

28. A device comprising a plurality of angularly spaced stop members, a plurality of means for supporting said stop members, means including a pinion for causing relative movement between each of said stop members and its supporting means, rotatable means for supporting said stop member supporting means, means to rotate said stop member supporting means intermittently through an angular distance substantially equal to the angular spacing of said threaded members, means including a gear for cooperating with the pinion of said stop member moving means to impart longitudinal movement to said stop members, means to bring said gear into meshing engagement with said pinion and to rotate said gear thereby to effect movement of said stop member, and means to restore said gear to its normal non-meshing position.

29. A device comprising, a plurality of angularly spaced stop members, each stop member having a threaded aperture, a plurality of elongated threaded members, one for each stop member extending through said apertures, a pinion carried by each of said elongated threaded members, spaced supporting members supporting said elongated threaded members adjacent their ends, a rotatable shaft to support said spaced support-

ing members, ratchet means to rotate said shaft intermittently through an angular distance substantially equal to the angular spacing of said stop members, a gear, means to position said gear for engagement with one of said pinions positioned for meshing engagement with said gear by rotation of said spaced supporting members, means to rotate said gear thereby to move said apertured stop member for adjustment, and means to restore said gear to its normal non-meshing position.

30. In a tuner for a radio receiver, a movable tuning device, means to retract said device to an extreme position, resilient means normally urging said device to another extreme position, a rotatable turret, said turret comprising a plurality of angularly spaced rotatable threaded members, stop members adapted to be engaged by said movable tuning device to limit the movement thereof in one direction, one for each of said threaded members, said stop members having threaded apertures for engagement with said threaded members, a pinion secured to each of said threaded members, a gear, means to position said gear for meshing engagement with the pinion on any one of said threaded members whereby to adjustably position the stops on said threaded members.

31. A tuner for a radio receiver comprising a movable tuning member, an adjustable stop for said member, means tending to move said member in one direction, means to retract said member in the opposite direction, and means operatively connected to said first named means for positioning said stop member in the path of movement of said tuning member when said retracting means moves said tuning member.

32. A tuner for a radio receiver comprising a movable tuning member, an electromagnet for moving said tuning member in one direction, means tending to move said tuning member in the opposite direction, an adjustable stop movable to intercept said movable tuning member upon deenergization of said electromagnet, whereby said stop member positions said movable tuning member at a definite point in its range of movement while moving under the influence of said last named means.

33. A tuner for a radio receiver comprising a longitudinally movable tuning member and a series of stops, and electrically operated means for rendering said stops effective in succession to arrest repeated movement of said movable tuning member upon movement thereof in one direction.

34. A tuner for a radio receiver comprising a movable tuning member, an adjustable stop for said member, means tending to move said member in one direction, means to retract said member in the opposite direction, means operatively connected to said first named means for positioning said stop member in the path of movement of said tuning member during movement of said tuning member under the influence of said retracting member, and means to adjust said stop while in its tuning member intercepting position.

35. In a tuner for a radio receiver, movable means for tuning said receiver from one end of its frequency range to the other, a plurality of adjustable abutments for said movable means, means to adjust said abutments comprising a rotatable member, means for supporting said member for longitudinal movement, a bearing, means to shift said bearing in the direction of movement of said member, and means for causing

said rotatable member to move with said bearing while permitting free rotation of said member.

36. In a tuner for a radio receiver, movable means for tuning said receiver from one end of its frequency range to the other, a plurality of adjustable abutments for said movable means, means for adjusting said abutments comprising a rotatable member, a distortable member providing a bearing for said rotatable member, means to confine said distortable member adjacent its margin whereby to provide for movement of said member with a snap action, and means for causing said rotatable member to move with said bearing while permitting free rotation of said member.

37. In a tuner for a radio receiver, a movable member for tuning said receiver, an adjustable abutment for said movable member, a threaded member engaging said abutment to adjust its position, a pinion secured on said threaded member, a rotatable shaft, a gear on said shaft to be brought into meshing engagement with said pinion, a fixed bearing for said shaft, said shaft being reciprocable in said bearing to bring said gear into mesh with said pinion, a movable bearing, said shaft being longitudinally fixed but freely rotatable in said movable bearing, means to move said movable bearing upon movement of said shaft, a support for said movable bearing comprising a distortable snap member, means for mounting said snap member under constraint to provide a snap action, said movable bearing thereby being retained in the position in which it is placed by movement of said shaft, means to confine said distortable member adjacent its margin whereby the configuration of said distortable member may be altered with a snap action upon applying pressure thereto, and means for causing said rotatable member to move with said bearing while permitting free rotation of said member.

38. In apparatus for the control of electrical equipment, a movable control member, electromagnetic means for moving said member, an adjustable abutment for positioning said member to exercise a predetermined control function on said electrical equipment, means to move said abutment into cooperating position with respect to said member, means movable to a position to adjust said adjustable abutment, switch means in a circuit with said electromagnetic means to operate the same, additional switch means in circuit with said first named switch means and said electromagnetic means, and means to operate said second named switch means upon movement of said movable adjusting means to abutment adjusting position whereby to prevent operation of said electromagnetic means while said adjusting means is in adjusting position.

39. In a tuner for a radio receiver, movable tuning means, electromagnetic means for moving said tuning means, an adjustable abutment for positioning said tuning means to tune said receiver to a desired frequency, means to move said abutment into tuning position with respect to said movable tuning means, means movable to a position to adjust said adjustable abutment, switch means in circuit with said electromagnetic means to operate the same, additional switch means in circuit with said first named switch means and said electromagnetic means, means to operate said second named switch means upon movement of said movable adjusting means to adjusting position, whereby to prevent operation

of said electromagnetic means while said adjusting means is in abutment adjusting position.

40. A tuning device for a radio receiver comprising: movable tuning means, electrically operated means for moving said tuning means in one direction, means for effecting a return movement of said tuning means when the supply of current to said electrically operated means is interrupted, and a stop member in the path of return travel of said movable tuning means for arresting the same in a desired preset station-receiving position.

41. A tuning device for a radio receiver comprising: movable tuning means, electrically operated means for moving said tuning means in one direction, means for effecting a return movement of said tuning means when the supply of current to said electrically operated means is interrupted, a stop member in the path of return travel of said movable tuning means, a switch for controlling the circuit to said electrically operated means, and means for adjusting said stop member including an element arranged to open said switch as said adjusting means is moved into active position.

42. A tuning device for a radio receiver comprising: movable tuning means, an electromagnet for moving said tuning means in one direction, means for effecting a return movement of said tuning means when said electromagnet is ineffective, a stop member in the path of return travel of said movable tuning means, and means for shifting said stop member during the ineffective period of said electromagnet to cause movement of said tuning means to a desired station-receiving position.

43. In a tuning device for radio receivers, movable tuning means, means for effecting movement of said tuning means in one direction from one extreme position of adjustment to the other, means for effecting a return movement of said tuning means, a rotatable turret having a plurality of circumferentially spaced stops adapted to be disposed singly in the path of return movement of said tuning means and to be engaged by said tuning means to arrest movement of said tuning means in a station-receiving position, and means operatively associated with said stops for indicating the station to which the receiver is tuned.

44. In a tuning device for radio receivers, movable tuning means, means for effecting movement of said tuning means in one direction, means for effecting a return movement of said tuning means, a turret, a shaft rotatably supporting said turret, said turret carrying a plurality of stops adapted to be disposed singly in the path of return movement of said tuning means and to be engaged by said tuning means to arrest movement of said tuning means in a station-receiving position, and dial means rotatable with said stops for indicating the station to which the receiver is tuned.

45. A device comprising: movable means adapted to be positioned in a plurality of different desired positions; a rotatable member; means rotatably supporting said rotatable member, said supporting means being relatively stationary with respect to said movable means; a plurality of angularly spaced stop means, one for determining each of said positions, mounted upon said rotatable member, said rotatable member being arranged for intermittent rotation about its axis to place said stop means in a position to be engaged by said movable

means to stop said movable means at said desired positions; and means for controlling the positions of said movable means including an electromagnet for moving said movable means away from said stop means, means responsive to movement of said movable means for effecting intermittent rotation of said stop means to normally index said angularly spaced stop means in a predetermined order in the path of movement of said movable means to stop said movable means at said desired positions during return movement of said movable means, and retracting means for returning said movable means toward said stop means.

46. A device comprising: movable means adapted to be positioned in a plurality of different desired stationary positions; a rotatable member; means rotatably supporting said rotatable member, said supporting means being relatively stationary with respect to said movable means; a plurality of angularly spaced stop means, one for determining each of said positions, mounted upon said rotatable member, said rotatable member being arranged for intermittent rotation about its axis to place said stop means in a position to be engaged by said movable means to stop said movable means at said desired positions; manually controlled means for effecting movement of said movable means away from said stop means; means responsive to movement of said movable means for effecting intermittent rotation of said stop means to normally successively index said angularly spaced stop means in the path of movement of said movable means to stop said movable means at said desired positions during return movement of said movable means; and automatic retracting means for returning said movable means toward and into engagement with said stop means.

47. A device comprising: a movable member adapted to be positioned in a plurality of different desired stationary positions; a rotatable member; means rotatably supporting said rotatable member, said supporting means being relatively stationary with respect to said movable means; a plurality of angularly spaced stop means, one for determining each of said positions, mounted upon said rotatable member, said rotatable member being arranged for intermittent rotation about its axis to place any one of said stop means in the path of movement of said movable member to stop said movable member at a corresponding one of said desired positions; electrical means for moving said movable member away from said stop means and effecting intermittent rotation of said stop means to successively index said angularly spaced stop means so as to remove one of said stop means from the path of movement of said movable member and to place another of said stop means in the path of movement of said movable member to stop said movable member at one of said desired positions during its return movement; and other means for moving said movable member back toward said stop means upon interruption of the current supply to said electrical means.

48. A device comprising: movable means adapted to be positioned in a plurality of different desired positions; a rotatable member; means rotatably supporting said rotatable member; a plurality of angularly spaced stops, one for determining each of said positions, carried by said rotatable member, said rotatable member being arranged for intermittent rotation about

its axis to place said stop means in position to stop said movable means at one of said desired positions; power means for moving said movable means away from said stop means; means for moving said movable means back toward and into engagement with said stop means, said last-mentioned means being capable of storing energy derived from said power means to provide a substantially uniform initial potential

force for effecting a return of said movable means; and means operable during the expenditure of said force and utilizing a portion of said force for rotating said rotatable member and 5 angularly indexing one of said stop means out of operative position with said movable means and for indexing another of said stop means into operative position.

CLARENCE W. WANDREY.
